(57) **CLAIM**

The ornamental design for an anal irrigation catheter adapted for use in an anal irrigation system, as shown and described.

DESCRIPTION

FIG. 1 is a perspective view of an anal irrigation catheter adapted for use in an anal irrigation system;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

In FIGS. 1-6 the broken lines illustrate a shaft portion of the anal irrigation catheter and form no part of the claimed design.

In FIGS. 1-5 the heavy dashed line illustrates the boundary of the claimed design.

1 Claim, 7 Drawing Sheets
